UNITED STATES PATENT OFFICE.

WALTER N. VANCE, OF CHICAGO HEIGHTS, ILLINOIS, ASSIGNOR TO DURAND STEEL LOCKER COMPANY, OF CHICAGO, ILLINOIS, A CORPORATION OF ILLINOIS.

BIN FRONT.

1,406,304.

Specification of Letters Patent. Patented Feb. 14, 1922.

Application filed June 14, 1920. Serial No. 388,714.

To all whom it may concern:

Be it known that I, WALTER N. VANCE, a citizen of the United States, residing in Chicago Heights, in the county of Cook and 5 State of Illinois, have invented a new and useful Improvement in Bin Fronts, of which the following is a specification.

This invention relates to metal shelving and has more particular reference to the 10 provision of a new and improved bin front or removable vertical wall for shelving wherein the shelves are supported upon shelf supports arranged in spaced slots in the shelving uprights.

15 The principal object of this invention is the provision of a strong and durable wall adapted for use as a bin front which may be easily inserted and removed and which when in position will be engaged in and 20 held by the slots of the said uprights.

Another important object is the provision 25 of a bin front construction which will not require any reformation of the other parts of the shelving to permit its use and which can therefore be incorporated in shelving already installed and be carried by the manufacturer as a mere attachment or supplemental part adapted for incorporation in 30 shelving constructions where its presence may be desired.

Numerous other objects and advantages of 35 the invention will be apparent as it is better understood from the following description when considered in connection with the accompanying drawing illustrating a preferred embodiment thereof.

Referring to the drawing,

Figure 1 is a partial front elevation of a shelf construction embodying my present invention;

Fig. 2 is a section taken substantially on the line 2—2 of Fig. 1;

Fig. 3 is a section taken substantially on the line 3—3 of Fig. 1;

45 Fig. 4 is an enlarged detail view of one of the bin front connectors, and

Fig. 5 is an enlarged side elevation of a portion of one of the uprights.

For the purpose of illustrating my invention I have shown on the drawing part of a metal shelf construction comprising rectangular tubular uprights 11 which it will be understood are arranged at the four corners of each shelf. Side walls 12 extend 55 from front to back between uprights and the

shelves indicated by reference character 13 are supported at the front and back upon shelf supports 14 engaged in the slots 15 of appropriate uprights. These slots are preferably of T-form, that is to say, they have 60 an upper relatively larger part 16 and a lower relatively smaller part 17. The shelf supports are interlocked in place by positioning their heads 18 through the larger parts 15 of the slots and moving the shelf supports down into the parts 17 to lock them 65 in place. The shelves in the present instance are of sheet metal construction the front edge being turned down at 18 and returned at 19 to provide a front vertical part 21 and 70 a flange 22 extending back in toward the lower edge of the shelf support. It will be understood that the shelves may be arranged in any number and at convenient heights by proper selection of the slots into 75 which the respective shelf supports are inserted for engagement. The bin front or vertical wall in the present instance comprises a metal sheet 23 of a length slightly less than the space between adjacent uprights 11 at the front. The longitudinal or horizontal edges of the wall 23 are bent to the U-form indicated at 24 and these U portions are disposed horizontally by bending the material on horizontal lines of bend 25. 80 Connectors shown in perspective in Fig. 4 are provided to support the bin front or vertical wall from the uprights and these connectors include a portion 26 having a hole or opening 27 and adapted to lie against the 85 rear face of the body of the wall. Each connector comprises a second part 28 bent at right angles to the part 26 and extending therebeyond at each end to provide lugs 29 which are bent outwardly at an angle as 90 shown. In the present instance these lugs are adapted to enter into the large parts of 95 appropriately arranged slots and where a rather narrow bin front is provided the lugs enter adjacent slots. The connectors are 100 fastened in place by bolts 31 extending through the body of the wall or bin front. The construction is such that this body of the wall is arranged back of the slots so that 105 the U-flanges extend over the slots and extend substantially to the plane of the vertical part 21 in the shelf. The bin front may be positioned by fastening one of the connectors in place, inserting it in appropriate slots, moving the bin front to desired posi- 110

tion and then positioning the other connector and then fastening it in place.

It will be manifest that this construction does not require any reformation of the uprights or the provision of complicated parts or parts expensive to manufacture.

It is thought that the invention and many of its attendant advantages will be better understood from the foregoing description and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A metal shelving comprising uprights having spaced slots, shelf supports mounted in said slots, shelves carried by said shelf supports, and a vertical wall adapted for arrangement between said uprights to extend up from said shelf, the body of said wall having detachable slot engaging members rigidly secured at its ends adjacent said uprights.

2. A metal shelving comprising uprights having slots for engagement by shelf supports, and a vertical wall arrangeable between said uprights and having detachable members each engaged in a plurality of said slots.

3. A metal shelving comprising uprights having slots for receiving shelf supports, said slots being of T form and a vertical wall adapted to be positioned between said uprights and having at each end oppositely bent lugs arrangeable in the larger parts of slots at each upright.

40 4. A metal shelving comprising uprights

having spaced shelf supports, receiving slots, a vertical wall adapted to be positioned between said uprights, and slot engaging extensions rigidly fastened to the ends of the body of said wall and adapted to protrude 45 into a plurality of said slots to secure said wall in place.

5. A metal shelving comprising uprights having spaced shelf support receiving slots, a vertical wall adapted to be positioned between said uprights, and slot engaging extensions rigidly fastened to the ends of said wall and adapted to protrude into a plurality of said slots to secure said wall in place, one of said extensions being removable to 55 permit said wall to be positioned and removed.

6. A metal shelving comprising uprights having shelf support receiving slots, a vertical wall arrangeable rearwardly of the said 60 slots and having fixed sheet metal extensions for engaging in a plurality of said slots.

7. A metal shelving comprising uprights having spaced shelf support receiving slots, a vertical wall having its horizontal edges 65 extending outwardly of the construction and over said slots, and a plurality of lips extending out from each end of said wall to engage in said slots.

8. A metal shelving comprising uprights 70 having spaced shelf support receiving slots, a vertical wall arrangeable between said uprights, and a metal plate having a portion adapted to be disposed in contact with said wall and secured thereto and having a second portion arranged angularly with respect to the first-mentioned portion and for engaging in the slots of an upright.

WALTER N. VANCE.
